(57) **CLAIM**

The ornamental design for a statuette light, as shown and described.

DESCRIPTION

FIG. 1 is a perspective view of a statuette light of the new design;

FIG. 2 is a top plan view of the statuette light of FIG. 1;
FIG. 3 is a bottom plan view of the statuette light of FIG. 1;
FIG. 4 is a left side elevational view of the statuette light of
FIG. 1; and,

FIG. 5 is a right side elevational view of the statuette light of
FIG. 1.

The portions of the Figures shown in broken lines are not
part of the claimed design and are for illustration purposes
only.
